DESIGN FOR A HELICOPTER

Agnew E. Larsen, Jenkintown, Pa., assignor, by
mesne assignments, to The Glenn L. Martin
Company, Baltimore, Md., a corporation of
Maryland

Application May 16, 1945, Serial No. 119,559

Term of patent 14 years

(Cl. D71—1)

To all whom it may concern:

Be it known that I, Agnew E. Larsen, a citizen
of the United States and resident of Jenkin-
town, in the county of Montgomery and State of
Pennsylvania, have invented a new, original, and
ornamental Design for a Helicopter, of which the
following is a specification, reference being had
to the accompanying drawings, forming part
thereof, in which

Figure 1 is a side elevational view of a heli-
copter showing my new design;

Fig. 2 is a front elevational view;

Fig. 3 is a side perspective view;

Figure 4 is a diagrammatical sectional view
taken on line 4—4 of Figure 1,

Figure 5 is a diagrammatical sectional view
taken on line 5—5 of Figure 1, and

Figure 6 is a diagrammatical sectional view
taken on line 6—6 of Figure 1.

The characteristic features of my design re-
side in the portions shown in full lines.

I claim:

The ornamental design for a helicopter, sub-
stantially as shown and described.

AGNEW E. LARSEN.
